UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 13,679, dated February 27, 1883.

Application filed January 25, 1883. Term of patent 3½ years.

To all whom it may concern:

Be it known that I, JULIUS PEGEL, of New York city, in the county of Westchester and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is a plain ground ornamented with scattered fret-like and border work, which stands out prominently in the design. Over this ground are disposed several large flower-and-leaf groups, consisting, as shown in the photograph, of central masses of leaves and flowers, from which spring out fern and blossom sprays. A, B, and C are the more prominent of these groups, all of which are clearly shown in the photograph.

I claim—

1. The design for a ground for a carpet, consisting of the ground *a*, substantially as shown and described. 25
2. The design for a carpet, consisting of the group A, substantially as shown and described.
3. The design for a carpet, consisting of the group B, substantially as shown and described. 30
4. The design for a carpet, consisting of the group C, substantially as shown and described.
5. The design for a carpet, consisting of the groups A, B, and C, and the smaller groups, 35 substantially as shown and described.
6. The design for a carpet, consisting of the groups A, B, and C, and the smaller groups, and the ground *a*, substantially as shown and described.

JULIUS PEGEL.
